UNITED STATES PATENT OFFICE.

HENRY GOODFRIEND, OF CHICAGO, ILLINOIS, ASSIGNOR TO UNIQUE LAMP & CASTING COMPANY, A COPARTNERSHIP, (CONSISTING OF HENRY GOODFRIEND, WILLIAM CHRISTENSEN, AND ALFRED E. LARSEN), OF CHICAGO, ILLINOIS.

DESIGN FOR AN ELECTRIC-LIGHTING FIXTURE.

Application filed October 14, 1925. Serial No. 15,120. Term of patent 3½ years.

To all whom it may concern:

Be it known that I, HENRY GOODFRIEND, a citizen of the United States, residing in the city of Chicago, in the county of Cook and State of Illinois, have invented a new, original, and ornamental Design for Electric-Lighting Fixture, of which the following is a specification, reference being had to the accompanying drawing, forming part thereof.

Figure 1 is a front elevation of the device.

Figure 2 is a top and bottom plan view of the device omitting a member of the top by which the device is suspended, and the pendant at the bottom. The same ornamentation is carried out in like manner on the other half of Figure 2.

I claim:

The ornamental design for an electric-lighting fixture, as shown.

HENRY GOODFRIEND.
